WEB GUIDING DEVICE

Edward F. Harmon, Flushing, N. Y., assignor to
E. I. du Pont de Nemours & Company, Wilming-
ton, Del., a corporation of Delaware

Original application December 13, 1935, Serial
No. 54,301. Divided and this application Jan-
uary 24, 1938, Serial No. 186,619

1 Claim. (Cl. 271—2.1)

This is a division of my application for patent
Serial No. 54,301, filed December 13, 1935.

The principal objects of this invention are to
provide an improved web guide for strip cellulose
or other sheet material; to provide means
for providing the sheet material with a little ten-
sion as it enters the guiding device, and to pro-
vide guide rolls engaging the web lightly and
guide rods between them to feed and guide the
web along its course.

Other objects and advantages of the inven-
tion will appear hereinafter.

Reference is to be had to the accompanying
drawings, in which

Fig. 1 is an elevation of the machine;

Fig. 2 is an elevation taken in the direction of
the arrow 2 in Fig. 1;

Fig. 3 is a sectional view on the line 3—3 of
Fig. 2;

Fig. 4 is a plan of the guide for the "Cello-
phane" on the line 4—4 of Fig. 2;

Fig. 5 is a plan of the feed rolls as indicated by
the arrow 5 in Fig. 3, and

Fig. 6 is a sectional view on the line 6—6 of
Fig. 2, showing the cutting knife and stop.

This invention is designed to employ a web of
"Cellophane" or other such material for pack-
aging tooth-brushes and other brushes. Cellu-
lose derivatives including esters and others and
even translucent and opaque materials can be
used. A roll of such material is supported in the
proper position and the material is drawn from
the roll, properly guided, and brought into a
position in which a plunger can force a separated
sheet of the material into a specially designed
former to produce a package or envelope for
receiving the bristles of the brush.

A driving shaft 29 is provided with means,
not shown, for driving a parallel shaft 44 in-
termittently and providing a quick action when
the shaft 44 is turning. This is done so that
the web can be cut into sheets at each dwell of
the web. The shaft 44 is shown as having a bevel
gear 43 driving a bevel pinion 47 on a feed roll
shaft 48. On the shaft 48 is a gear 49 meshing
with a companion gear. These two gears are
mounted on parallel shafts which carry a pair
of circumferentially grooved feed rolls 50 and
50a. One of these is of metal and the other
of rubber.

A web of "Cellophane" or the like is stored on
a roll 108 which has axial handles 109 by which
it can be lifted and placed in open topped bear-
ings 110. This roll is free to rotate but is sup-
plied with an adjustable brake 111. These feed
rolls are for the purpose of drawing the web
over a roll 51 on a shaft 52 carried by a bracket

on the frame. The web passes through a guide
and tensioning device 53 which comprises a
bracket 54 carried in stationary position and a
pivoted plate 55 which is latched in place by a
latch 56. Both this guide and the bracket are
provided with projecting ribs 57 which do not
quite touch but serve to provide a little tension
for the web. This guide guides the web between
two series of vertical rods 58 located in grooves
in the feed rolls which keep the web in place
while it is passing downwardly. The feed rolls
are arranged so that they engage the web light-
ly but sufficiently to feed it. The guide rods 58
are carried by supports 59 on one of two former
frames 61. The web is fed down in front of a 15
stationary plate 62 intermittently. The shaft
29 carries a gear 45 constantly driving a sleeve
112, loose on the shaft 44, through a gear 46.
As the web comes down through the guides 58 it
is cut off, at each dwell, into equal sheets by a
pivoted knife blade 65 cooperating with a second
cutting surface and operated by a cam 66 on the
sleeve 112. When the cam is out of operation a
spring 67 brings the knife blade back against an
adjustable stop 68.

The plate 62, against the front of which the
severed sheet of "Cellophane" or the like is
brought from the guides 58, is provided with a
shield 70 having a vertical slot 71 therein. A
sliding bar 72, provided with smooth sides, is
pushed in through the slot 71, which has an en-
larged portion through the center to receive the
bar 72. The sliding bar 72 constitutes the means
for advancing the sheets out of the guide.

It will be seen that this machine takes a
continuous strip of sheet material, of which the
envelope is to be made, feeds it down in front
of an opening, and cuts it off into separate rec-
tangular sheets.

Having thus described my invention and the
advantages thereof, I do not wish to be limited
to the details herein disclosed, otherwise than
as set forth in the claim, but what I claim is:

The combination of a tension guide through
which a web passes having longitudinal con-
tinuous ribs on opposite sides for lightly engag-
ing the web at opposite points and applying
tension thereto, two series of rods on opposite
sides of said web in position to receive the web
from the tension guide, and a pair of rolls beyond
said guide one made up of metal and the other of
soft surfaced cylindrical surfaces, half of said
rolls passing between the metal surfaces and the
other half between the soft surfaces of the rolls
and both series extending downwardly beyond the
rolls and constituting guides for the web.

EDWARD F. HARMON.
